NORMALLY DEENERGIZED CODED
SIGNALING SYSTEM

Arthur L. Jerome, Edgewood, Pa., assignor to The
Union Switch & Signal Company, Swissvale,
Pa., a corporation of Pennsylvania

Application December 7, 1943, Serial No. 513,229

19 Claims. (Cl. 246—26)

My invention relates to an improved railway signaling system which operates without line wires and is arranged so that the apparatus for each track section is normally deenergized and becomes energized on the approach of a train and becomes deenergized on passage of a train through the track section.

It is an object of this invention to provide an improved system of the type described which operates to provide a two-block three-indication signaling system.

Another object of the invention is to provide a system of the type described which is arranged so that the lamps of the wayside signals are normally extinguished and become lighted only when the adjacent section in the rear is occupied.

A further object of the invention is to provide a system of the type described which is arranged so that appropriate signal indications will be provided for the second of two trains regardless of how closely it follows the first train.

Another object of the invention is to provide a system of the type described which may be employed in track stretches through which are operated locomotives equipped with cab signal apparatus responsive to flow of coded alternating current in the track rails.

I shall describe two forms of normally deenergized coded signaling system embodying my invention, together with a modification thereof of which I may employ, and shall then point out the novel features thereof in claims.

In practicing my invention, I supply to the rails of the adjacent section in advance of a train at the entrance end of the section master code of one polarity. This operates equipment at the exit end of the section to cause master code of the other polarity to be supplied to the next or second section in advance to detect occupancy thereof without causing master code to be repeated into the third section in advance. Master code supplied over the rails of a section causes feed-back energy to be supplied over the section rails, while the polarity of the feed-back energy is governed by presence or absence of feed-back energy in the section in advance and the wayside signals are controlled by the feed-back energy. The system is arranged so that when a section is occupied energy is supplied to the section rails at the exit end thereof to detect when the section is vacated and to discontinue operation of the equipment for that section when the section is vacated.

Where the system is applied to a track stretch through which are operated locomotives equipped with cab signal apparatus responsive to flow of coded alternating current in the track rails, the code frequency of the energy supplied to the rails of an occupied section at the exit end thereof is

governed by occupancy of the adjacent section in advance.

In the drawings, Figs. 1A and 1B are a diagram of a stretch of track equipped with wayside signaling apparatus embodying this invention.

Figs. 2A and 2B are a diagram of a stretch of track equipped with signaling apparatus embodying this invention and adapted for use in stretches where cab signals are employed, and

Fig. 3 is a diagram of a modification which may be employed in the system shown in Figs. 2A and 2B.

Similar reference characters refer to similar parts in each of the several views.

In most instances the relay contacts are shown directly beneath the winding of the relay, but in some cases, in order to simplify the drawings, relay contacts are shown separated from the relay winding, and where this is done the relay with which the contacts are associated are designated by appropriate reference characters placed directly over the contacts.

In Figs. 1A and 1B of the drawings there is shown a stretch of railway track having track rails 1 and 2 over which traffic normally moves in the direction indicated by the arrows, that is, from left to right. The rails of the track stretch are divided by insulated joints 3 into track sections for signaling purposes. These track sections are designated 1T, 2T, 3T, etc. in the drawings, while each of these track sections has at the entrance end thereof a wayside signal designated S with an appropriate prefix. As shown, the wayside signals are of the familiar color light type, and each has a red or stop lamp R, a yellow or caution lamp Y, and a green or clear lamp G.

Each track section is provided with a track circuit having at each end thereof a polar track relay P and a code following neutral or polar biased neutral track relay N connected in series across the section rails. The track relays MP and MN at the exit end of each section are operated by master code supplied over the section rails from the track battery TB, while the track relays FP and FN at the entrance end of each track section are operated by feed-back energy supplied from the feed-back battery FB.

The equipment is shown in the condition which it assumes when the track stretch is vacant. At this time all of the equipment is deenergized so that all of the relays are released and all of the signal lamps are extinguished except the red lamp R of signal 1S which controls entrance of traffic into the track stretch.

When it is desired to permit a train to enter the track stretch, a slow releasing control relay CR is picked up and its contact 10 establishes a circuit for a coding device 1CT which controls

connection of the track battery 1TB and of track relays 1FP and 1FN with the rails of section 1T. The pick-up circuit for relay CR may be established by depressing a push-button PB, or it may be established by any other appropriate means as, for example, by a lever of an interlocking machine or by approach of a train.

The coding device 1CT and the corresponding devices for the other track sections have contacts biased to a released position in which they connect the track relays across the section rails, while the contacts of each of these coding devices, when the device is energized, are moved to their picked-up positions a predetermined number of times each minute. Although any code speed may be employed in this system, it is preferred to employ a relatively high code of speed, such as 180 code impulses per minute, to insure prompt shunting when a train enters a section, and to also insure prompt response of the apparatus on the supply of energy to an unoccupied section.

On picking up of control relay CR and resultant supply of energy to coding device 1CT, its contacts 12 and 13 pick up and cause energy to be supplied from the battery 1TB to the rails of section 1T. As contacts 15 and 16 of relay CR are picked up, the energy supplied from battery 1TB to the section rails is of normal polarity, that is, the positive terminal of the battery is connected to the lower track rail 2. The energy supplied to the section rails feeds over back contacts 18 and 19 of impulse relay 1IR to track relays 1MP and 1MN and moves the contacts of relay 1MP to their left-hand or normal position, or holds them in that position if they are already in such position, while this energy picks up the contact of relay 1MN so that an impulse of energy is supplied through the decoding transformer 1MDT to relay 1MH.

On release of the contacts of coding device 1CT, the supply of energy from track battery 1TB to the relays 1MP and 1MN is cut off and the contacts of relay 1MP remain in their normal positions, while the contact of relay 1MN releases so that an impulse of energy is supplied through the decoding transformer 1MDT to relay 1MH. In addition, on release of relay 1MN an impulse of energy is supplied from the decoding transformer 1MDT over back contacts 20 and 21 of relay 2SR to relay 1IR and its contacts 18 and 19 pick up to cause energy to be supplied from battery 1FB to the rails of section 1T. Energy was also supplied to relay 1IR from the transformer 1MDT on picking up of relay 1MN, but the relay 1IR is of a type which responds to energy of one polarity only, and the equipment is arranged so that energy of the polarity effective to pick up the relay contacts is supplied to the relay on release of relay 1MN.

On picking up of relay 1MH, energy is supplied over its front contact 23 and normal polar contact 25 of relay 1MP to relay 2LR, while when relay 2LR picks up, its contact 26 establishes a stick circuit for the relay including normal polar contact 25 of relay 1MP. In addition, on picking up of relay 2LR, its contact 28 establishes a circuit for coding device 2CT so that it operates to supply master code energy from track battery 2TB to the rails of section 2T. At this time, relay 2SR is released so the energy supplied from battery 2TB to the rails of section 2T is of reverse polarity, that is, the positive terminal of the battery is connected to the upper track rail.

The energy of reverse polarity supplied to the

rails of section 2T feeds over back contacts 30 and 31 of relay 2IR to track relays 2MP and 2MN and moves the contacts of relay 2MP to their right-hand or reverse position and picks up the contact of relay 2MN so that energy is supplied through the decoding transformer 2MDT to relay 2MH. On picking up of relay 2MH, energy is not supplied to relay 3LR since polar contact 34 of relay 2MP is in its right-hand or reverse position. Accordingly, relay 3LR remains released and does not establish the circuit of coding device 3CT so energy is not supplied to the rails of section 3T. As a result, relay 3FHP remains released and causes the energy supplied from battery 2FB to the rails of section 2T to be of reverse polarity.

On release of the contacts of coding device 2CT, the track relay 2MN releases and an impulse of energy is supplied from the decoding transformer 2MDT over back contacts 35 and 36 of relay 3SR to relay 2IR and its contacts 30 and 31 pick up and cause an impulse of energy to be supplied from battery 2FB to the rails of section 2T. This energy feeds over back contacts 38 and 39 of coding device 2CT to track relays 2FP and 2FN and moves the contacts of relay 2FP to their reverse position and picks up the contact of relay 2FN so that energy is supplied through the transformer 2FDT to relay 2FH and its contacts pick up and establish a circuit for relay 2FHP.

When relay 2FHP picks up, its contacts 40 and 41 cause the energy supplied from battery 1FB to the rails of section 1T to be of normal polarity, that is, the positive terminal of the battery is connected to the lower track rail 2. Energy supplied from battery 1FB during the picked-up periods of relay 1IR feeds over back contacts 12 and 13 of coding device 1CT to track relays 1FP and 1FN and moves the contacts of relay 1FP to their left-hand or normal positions and operates relay 1FN so that energy is supplied through the transformer 1FDT to relay 1FH and it is picked up. When relay 1FH picks up, its contact 43 completes a stick circuit for relay CR including front contact 44 of relay CR to maintain relay CR picked up after release of the push-button PB. Accordingly, contact 10 of relay CR maintains the circuit of coding device 1CT, while contacts 15 and 16 of relay CR cause the energy supplied from battery 1TB to the rails of section 1T to be of normal polarity.

As long as the control relay CR or the relay 1FH is released, the red lamp R of signal 1S is lighted, but when both of these relays pick up, the circuit of the red lamp R of signal 1S is interrupted and energy is supplied over front contact 45 of relay CR, front contact 46 of relay 1FH, and normal polar contact 48 of relay 1FP to the green lamp G of signal 1S.

It will be seen, therefore, that when the control relay CR is picked up to initiate operation of the system, master code of normal polarity is supplied to the rails of section 1T and causes master code of reverse polarity to be supplied to the rails of section 2T. Master code of reverse polarity supplied to a track section will not cause master code to be supplied to the next section so the supply of master code is not repeated beyond the second track section. Master code of either polarity supplied over the rails of a track section causes feed-back energy to be supplied over the section rails, while the polarity of the feed-back energy in a track section is governed by the feed-back detector relay for the section in ad-

vance. Accordingly, feed-back energy of normal polarity is supplied to the rails of section 1T and signal 1S is caused to display its green or clear indication, while feed-back energy of reverse polarity is supplied over the rails of section 2T with the result that signal 2S, if lighted, will display its yellow or caution indication. At this time, however, relay 1MH is picked up and its contact 23 interrupts the circuit of the lamps of signal 2S.

If a train now accepts the proceed indication displayed by signal 1S and advances into section 1T, the supply of both master code and feed-back energy over the section rails is cut off and relays 1MH and 1FH release.

On release of relay 1FH its contact 43 interrupts the stick circuit for relay CR and the contacts of relay CR release to additionally interrupt the relay stick circuit, to deenergize coding device 1CT to reverse the connections for supplying energy from the battery 1TB to the rails of section 1T, and to cause signal 1S to display its red or stop indication.

On release of relay 1MH its contact 23 interrupts the pick-up circuit for relay 2LR but this relay is held picked up at this time by its stick circuit including its own front contact 26, so that energy is supplied over back contact 48 of relay 1MH and front contact 49 of relay 2LR to relay 2SR.

When relay 2SR picks up, its contacts 51 and 52 change the energy supplied from track battery 2TB to the rails of section 2T from reverse to normal polarity with the result that the contacts of relay 2MP move to their left-hand or normal positions so that energy is supplied over front contact 54 of relay 2MH and normal polar contact 34 of relay 2MP to relay 3LR and its contacts pick up. Accordingly, its contact 55 establishes a stick circuit for the relay, while its contact 57 establishes a circuit for coding device 3CT and it operates to supply energy from track battery 3TB to the rails of section 3T. As explained in connection with section 2T, master code of reverse polarity supplied to the rails of track section 3T will not cause master code to be supplied to the next section, but will cause feed-back energy to be supplied over the section rails so that relay 3FH picks up and establishes a circuit for relay 3FHP. When relay 3FHP picks up, its contacts 59 and 60 change the energy supplied from battery 2FB to the rails of section 2T from reverse to normal polarity, and as a result of this change, the contacts of relay 2FP move from their reverse to their normal positions so that the circuit of the green lamp G of signal 2S is established.

As pointed out above, on entrance of the train into section 1T, the relay 1MH released, and on release of its contacts energy is supplied over its back contact 23, front contact 62 of relay 2LR, front contact 63 of relay 2FHP, and normal polar contact 65 of relay 2FP to the green or clear lamp G of signal 2S so that the engineer of the train in section 1T will be advised that the two adjacent track sections in advance are unoccupied.

As long as section 2T is vacant, the relay 2MH is picked up and prevents the supply of energy to the lamps of signal 3S so this signal is not lighted at this time. As section 2T is not occupied, it is unnecessary for the lamps of signal 3S to be lighted.

On entrance of the train into section 1T and resultant picking up of relay 2SR, its contacts 20 and 21 transfer control of relay 1IR from the

decoding transformer 1MDT to a circuit controlled by contacts 67 and 68 of coding device 2CT, and by front contacts 70 and 71 of relay 2LR. Accordingly, relay 1IR is operated to supply energy from the battery 1FB to the rails of section 1T, and to connect track relays 1MN and 1MP to the section rails, but as the section is occupied, operation of relay 1IR has no effect.

From the foregoing, it will be seen that when 10 the train enters section 1T, the polarity of the master code supplied to section 2T is changed to thereby cause master code to be supplied to section 3T, while feed-back energy supplied over the rails of section 3T causes the feed-back energy supplied to the rails of section 2T to be of normal polarity so that signal 2S displays its green or clear indication. In addition, when the train enters section 1T, the lamps of signal 2S are lighted, while relay 1IR is operated by a code 15 transmitter to supply energy to section 1T to discontinue operation of the equipment for section 1T when that section is vacated, as will be explained hereafter.

When the train advances into section 2T, the 25 supply of energy over the rails of this section is cut off and relays 2FH and 2MH release. Release of relay 2FH results in release of relay 2FHP and its contact 63 establishes the circuit of the red lamp R of signal 2S, while contacts 40 and 41 of relay 2FHP change the energy supplied from battery 1FB to the rails of section 1T from normal to reverse polarity.

On release of relay 2MH, energy is supplied 30 over its back contact 73 and front contact 74 of relay 3LR to relay 3SR and its contacts pick up to cause energy of normal polarity to be supplied from battery 3TB to the rails of section 3T, and to transfer control of relay 2IR from the decoding transformer 2MDT to the coding device 3CT. On the supply of master code of normal polarity to the rails of section 3T, the equipment at the exit end of this section causes master code of reverse polarity to be supplied to the next section in advance so that feed-back energy 35 is supplied over the rails of that section to thereby cause feed-back energy of normal polarity to be supplied over the rails of section 3T and thus cause signal 3S to display its green or clear indication. At this time, energy is supplied to the 40 lamps of signal 3S over the circuit which includes back contact 54 of relay 2MH and front contact 76 of relay 3LR.

When the train vacates section 1T, energy of 45 reverse polarity supplied to the section rails from battery 1FB as a result of operation of relay 1IR by coding device 2CT feeds over back contacts 12 and 13 of coding device 1CT to track relays 1FN and 1FP and operates relay 1FN so that relay 1FH picks up and its contact 78 establishes 50 a circuit for coding device 1CT and it operates to supply energy from battery 1TB to the rails of section 1T. At this time, relay CR is released so its contact 45 maintains the circuit of the red lamp R of signal 1S, while its contacts 15 and 16 cause the energy supplied from battery 1TB to the rails of section 1T to be of reverse polarity.

The energy supplied from battery 1TB to the 55 rails of section 1T feeds to the track relays 1MP and 1MN during a released period of the contacts of relay 1IR and moves the contacts of relay 1MP to their right-hand or reverse position in which contact 25 interrupts the stick circuit for relay 2LR.

On release of relay 2LR, its contacts 70 and 71 interrupt the circuit controlled by coding device 2CT for operating the relay 1IR and the contacts of relay 1IR thereafter remain released and energy is no longer supplied from battery 1FB to the rails of section 1T and relay 1FN ceases to follow code so relay 1FH releases and its contact 78 interrupts the circuit of coding device 1CT so that it ceases to cause energy to be supplied from battery 1TB to the rails of section 1T. Accordingly, track relay 1MN thereafter remains released and relay 1MH releases.

On release of relay 2LR, its contact 49 interrupts the circuits of relay 2SR, but the relay 2SR is of a type the contacts of which are slow to release so contacts 20 and 21 of relay 2SR remain picked up for a period subsequent to release of relay 2LR and do not connect relay 1IR to the secondary winding of transformer 1MDT. The relay 2SR is sufficiently slow in releasing that its contacts remain picked up and interrupt connection of the relay 1IR with transformer 1MDT long enough after release of relay 2LR to insure that relay 1FH has released and coding device 1CT has ceased to cause energy to be supplied to the rails of section 1T. This insures that, when relay 1IR is connected to transformer 1MDT, there is no possibility that relay 1IR will be operated by energy from the transformer and thus cause energy to be supplied to the rails of section 1T.

If relay 2SR should release and connect relay 1IR to transformer 1MDT before track relay 1MN ceases to be operated by energy supplied over the section rails, the relay 1IR would be operated by impulses of energy from transformer 1MDT and would cause energy to be supplied from battery 1FB to the rails of section 1T. This energy would operate track relay 1FN and keep relay 1FH picked up and thus maintain the circuit of coding device 1CT and thereby continue the supply of energy to section 1T with the result that the equipment for the section would continue to operate. Any possibility of failure of the equipment to cease operation when a section is vacated may be eliminated by making the release time of relay 2SR long enough to be certain that relay 1IR is not connected to the decoding transformer until after the track relay 1MN ceases to operate.

In addition, on release of relay 2LR, its contact 62 interrupts the circuit of the lamps of signal 2S and this signal is now dark, while contact 28 of relay 2LR interrupts the circuit of coding device 2CT and thus discontinues supply of energy to the rails of section 2T.

In like manner, when the train vacates section 2T, energy of reverse polarity supplied from battery 2FB to the section rails as a result of operation of relay 2IR by coding device 3CT feeds to relays 2FP and 2FN and operates relay 2FN to pick up relay 2FH so that its contact 82 establishes a circuit for coding device 2CT. Accordingly, the device 2CT operates to supply energy of reverse polarity from battery 2TB to the rails of section 2T and this energy feeds to track relays 2MP and 2MN during released periods of the contacts of relay 2IR. This energy is of reverse polarity because the relay 2SR is released, while this energy causes the contacts of relay 2MP to move to their reverse position in which contact 34 interrupts the circuit of relay 3LR so that relay 3LR releases and discontinues operation of relay 2IR by coding device 3CT, while relay 3SR remains picked up, as explained in connection with relay 2SR, to disconnect relay 2IR

from the decoding transformer 2MDT. The contacts of relay 2IR, therefore, remain released and do not cause energy to be supplied from battery 2FB to the section rails but connect the track relays 2MP and 2MN across the section rails.

When the supply of energy to the exit end of section 2T is cut off, the track relay 2FN remains released and relay 2FH releases to interrupt the circuit of coding device 2CT and thus cut off the supply of energy from battery 2TB to the rails of section 2T. This causes relay 2MN to cease to follow code so relay 2MH releases, while relay 3SR thereafter releases to reconnect relay 2IR to transformer 2MDT, and to cause the energy supplied from battery 3TB to the rails of section 3T to be of reverse polarity.

The equipment for each of the other sections in the track stretch operates in a similar manner so that, when a train enters a track section, energy is supplied over the section rails to detect when the section is vacated and to thereupon discontinue operation of the track circuit apparatus for that section.

This system also operates to provide appropriate signal indications for a second or following train. For purposes of illustration, it will be assumed that the train considered above stops in section 3T and that a second train is admitted to the track stretch. In order to cause signal 1S to display a permissive indication, the push-button PB is depressed to pick up control relay CR and cause master code of normal polarity to be supplied to the rails of section 1T. This causes master code of reverse polarity to be supplied to the rails of section 2T so that feed-back energy is supplied over the rails of section 2T and causes feed-back energy of normal polarity to be supplied over the rails of section 1T and thus cause signal 1S to provide its green or clear indication.

If the second train now enters section 1T, the supply of master code of normal polarity over the rails of this section is cut off and relay 1MH releases and establishes the circuit including front contact 49 of relay 2LR for energizing relay 2SR. When relay 2SR picks up, it changes the energy supplied from battery 2TB to the rails of section 2T from reverse to normal polarity. Master code of normal polarity supplied to the rails of section 2T causes the contacts of relay 2MP to occupy their left-hand or normal positions so that energy is supplied to relay 3LR over the circuit which includes front contact 54 of relay 2MH and normal polar contact 34 of relay 3LR. Accordingly, the contacts of relay 3LR pick up and energy is supplied over its front contact 57 to coding device 3CT and it operates to supply energy of reverse polarity from battery 3TB to the rails of section 3T.

However, as section 3T is assumed to be occupied, master code supplied to the section rails does not reach the exit end of the section and does not cause feed-back energy to be supplied over the section rails. Accordingly, relays 3FH and 3FHP remain released and the feed-back energy supplied from battery 2FB to the rails of section 2T is of reverse polarity so the contacts of relay 2FP remain in their right-hand or reverse positions and contact 65 establishes the circuit of the yellow lamp Y of signal 2S. When the first train is in section 3T, the second or following train will receive a caution indication from signal 2S and will be prepared to stop before entering section 3T.

As pointed out above, when the first train enters section 3T, the equipment at the exit end of

that section is conditioned to cause the relay 3IR, not shown, to be operated by the coding device for the adjacent section in advance to supply energy of reverse polarity to the rails of section 3T.

If, while the second train is in section 1T, the first train vacates section 3T, the signal equipment will operate to provide the proper signal indications for the second train. When the first train vacates section 3T, master code of reverse polarity supplied at the entrance end of the section as a result of energization of coding device 3CT over the circuit established by contact 57 of relay 3LR, feeds over the section rails, while energy from battery 3FB, not shown, supplied to the section rails at the exit end of the section as a result of operation of relay 3IR by the coding device for section 4T also feeds over the section rails.

The energy of reverse polarity supplied to the section rails at the entrance end of the section feeds to the track relays at the exit end of the section and moves the contacts of relay 3MP, not shown, to their reverse position to interrupt the circuit of relay 4LR, not shown, and thereby discontinue operation of relay 3IR by the coding device and to also interrupt the circuit of relay 4SR. After a short time interval, relay 4SR releases and connects relay 3IR to the associated decoding transformer so that the relay 3IR thereafter functions as a feed-back impulse relay and continues to cause impulses of energy of reverse polarity to be supplied to the rails of section 3T at the exit end thereof.

The energy of reverse polarity supplied to the rails of section 3T at the exit end thereof feeds to track relays 3FP and 3FN and operates relay 3FN so that relay 3FH picks up and causes the slow release repeater relay 3FHP to pick up. When relay 3FHP picks up, its contacts 59 and 60 change the energy supplied from battery 2FB to the rails of section 2T from reverse to normal polarity so that the contacts of relay 2FP move to their left-hand or normal positions and establish the circuit of the green or clear lamp G of signal 2S.

As explained above, when a train vacates a section and energy of reverse polarity is supplied from the entrance end of the section to the exit end thereof, the relay LR releases to discontinue operation of relay IR by the coding device, while a time interval must elapse before relay SR releases to connect relay IR to the decoding transformer. In this time interval relay IR does not operate to supply energy to the section rails and the relay FH at the entrance end of the section releases. However, the relays FH control slow releasing repeater relays FHP, which are slow enough in releasing to remain picked up during this release of the relays FH. Accordingly, the relays FHP prevent momentary flashes of the red signal lamps, and momentary reversal of the polarity of the feed-back energy supplied to the section in the rear and consequent momentary display of the yellow indication by the signal for that section.

From the foregoing, it will be seen that if a second train is in section 1T and the first train vacates section 3T, the equipment operates to change the indication provided by signal 2S from yellow to green so that the engineer of the second train is informed of the change in traffic conditions in advance.

This system also operates to provide proper control of the signals if the second train advances

into section 2T before the first train vacates section 3T.

As pointed out above, when the second train entered section 1T, the supply of master code of normal polarity over the rails of section 1T is cut off, and relay 1MH releases with the result that energy is supplied over back contact 48 of relay 1MH and front contact 49 of relay 2LR to relay 2SR. Accordingly, relay 2SR picks up and changes the master code supplied to the entrance end of section 2T from reverse to normal polarity. On the supply of master code of normal polarity over the rails of section 2T, relay 3LR is picked up to cause coding device 3CT to operate to supply master code of reverse polarity to the rails of section 3T, but as section 3T is assumed to be occupied, this supply of master code to the section rails is without effect.

If, while the first train is in section 3T, the second train advances into section 2T, the supply of master code over the rails of section 2T will be cut off and relay 2MH will release so that energy is supplied over its back contact 13 and front contact 14 of relay 3LR to relay 3SR and it picks up to cause the energy supplied to section 3T to be of normal polarity. As long as section 3T is occupied, master code of normal polarity supplied to the section rails has no effect, but when the first train vacates section 3T, this energy feeds to the exit end of the section and causes the contacts of track relay 3MP, not shown, to move to their normal positions to establish the pick-up circuit of relay 4LR, not shown, while relay 3MH picks up to interrupt the circuit of relay 4SR. At the expiration of the release time of relay 4SR, the relay 3IR operates as a feed-back impulse relay and causes feed-back energy of appropriate polarity to be supplied to the rails of section 3T to control signal 2S, and the equipment thereafter operates in the usual manner.

This system also operates to provide the proper control of the signals if a train enters a track section before the preceding train vacates the track section. For purposes of illustration, it will be assumed that a train stops in section 2T, and that a second train enters this section before the first train vacates the section.

As previously explained, when the first train entered section 2T, the relay 3SR picked up so that relay 2IR is operated by coding device 3CT and causes energy to be supplied from battery 2FB to the rails of section 2T. As section 2T is assumed to be occupied by the first train, the energy supplied to the section rails from battery 2FB is without effect, while entrance of the second train into section 2T has no effect. If the second train should vacate section 1T, operation of the equipment for that section would be discontinued in the usual manner.

When the first train vacates section 2T, the relay 2IR continues to be operated by coding device 3CT and energy continues to be supplied from battery 2FB to the rails of section 2T, but because of the presence of the second train in the section, this energy is without effect and there is no change in the condition of the equipment for section 2T.

At this time, as relay 3SR is picked up and as relay 3LR is also picked up, the coding device 3CT operates to supply master code of normal polarity to the rails of section 3T. As long as the first train is in section 3T, the master code supplied at the entrance end of the section has no effect, but if the first train vacates section 3T before the second train enters the section, the

master code supplied to the entrance end of the section will cause the equipment at the exit end of the section to supply master code to the next section in advance and to supply feed-back energy over the rails of section 3T to cause signal 3S to display a permissive indication.

As pointed out above, when the first train vacates section 2T, the relay 3LR is picked up, while relay 2MH is released so the circuit for supplying energy to the lamps of signal 3S is complete and a lamp of this signal is lighted to indicate to the engineer of the second train the condition of occupancy of the adjacent section in advance.

When the second train vacates section 2T, the equipment for this section operates in the usual manner to detect when the section is vacated and to thereafter discontinue operation of the equipment for that section.

The principle employed in the system shown in Fig. 1 may be employed in a signaling system operating without wayside signals and adapted for use in track stretches through which are operated locomotives equipped with cab signal apparatus responsive to flow of coded alternating current in the track rails and Fig. 2 is a diagram showing this modification of the invention.

System shown in Fig. 2

In the modification shown in Fig. 2, the stretch is without wayside signals except for a signal 1S which governs entrance of trains into the protected stretch.

The construction and operation of the cab signal apparatus on the locomotives operated in the track stretch are not a part of this invention and this apparatus may be constructed as shown in Letters Patent of the United States No. 1,986,679 of L. V. Lewis.

The equipment is shown in the condition which it assumes when the track stretch is vacant and before it is prepared for passage of a train therethrough. At this time all of the relays are released and all of the coding devices are deenergized, while the red lamp R of signal 1S is lighted by energy supplied over back contact 45 of relay CR.

When it is desired to prepare the stretch to permit passage of a train therethrough, the push-button PB is depressed to establish a pick-up circuit for the slow releasing control relay CR and its contacts pick up so that energy is supplied over its front contact 10 to coding device 1CT with the result that it operates to supply energy from the battery 1TB to the rails of section 1T through the winding of relay 1FT in the wrong direction to pick up the contacts of the relay 1FT. The energy supplied to the rails of section 1T feeds over back contacts 100 and 101 of coding relay 1CTP to relay 1MT and operates it so that energy is supplied through the decoding transformer 1MDT to relay 1MH and to relay 1IR. The relay 1IR is of a type the contact of which will be picked up only on supply of energy of one polarity thereto, and the equipment is arranged so that energy of this polarity is supplied to the relay on release of the contact of relay 1MH. Accordingly, on continued operation of relay 1MT subsequent to picking up of the contacts of relay 1MH, an impulse of energy is supplied to coding relay 1CTP each time the contacts of relay 1MT release. The circuit for supplying energy to relay 1CTP includes front contact 103 of relay 1MH, front contact 104 of relay 1IR, back contact 106 of relay 2SR, and back contact 105 of relay 2Q.

The energy supplied to relay 1CTP picks up its contacts momentarily and, during the picked-up periods of the relay contacts, energy is supplied from battery 1FB to the rails of section 1T. 5 This energy feeds to relay 1FT over the back contact of coding device 1CT and operates relay 1FT so that energy is supplied through the decoding transformer 1FDT to relay 1FH. The contacts of relay 1FH, therefore, pick up so that 10 front contact 43 of relay 1FH completes the stick circuit including front contact 44 of relay CR to maintain the relay CR picked up. In addition, on picking up of relay 1FH, the circuit of the red lamp R of signal 1S is interrupted and energy is supplied over front contact 45 of relay CR and front contact 46 of relay 1FH to the yellow lamp Y of signal 1S to thereby indicate that the stretch is prepared for passage of a train therethrough.

15 On the supply of energy to section 1T and operation of relay 1MT to pick up relay 1MH, energy is supplied over front contact 108 of relay 1MH and back contact 109 of relay 2Q to relay 2LR, while on picking up of relay 2LR, its contact 110 establishes a stick circuit to maintain the relay picked up as long as relay 2Q is released.

At this time, relay 2SR is released so the tuned alternator controlled thereby is deenergized, while 30 the primary winding of track transformer 1TT is short-circuited over back contact 111 of relay 2SR to reduce impedance of the transformer secondary winding and minimize arcing at the contacts of relay 1CTP.

35 If a train now enters section 1T, the supply of energy over the rails of this section will be cut off and relay 1FH will release so that its contact 43 interrupts the stick circuit for relay CR so it releases and cuts off operation of coding device 1CT, while the circuit of the yellow lamp Y of signal 1S is interrupted and the circuit of the red lamp R is established.

In addition, at this time relay 1MH releases with the result that energy is supplied over its 45 back contact 108 and front contact 112 of relay 2LR to relay 2SR and its contacts pick up so that its front contact 114 establishes a stick circuit to maintain the relay picked up as long as relay 2LR is picked up. On picking up of relay 50 2SR, its contact 115 establishes the circuit of code transmitter 180CT, while its contact 117 establishes the circuit of code transmitter 75CT.

On operation of code transmitter 180CT, the coding relay 2FCT is operated to supply energy 55 to the rails of section 2T and this energy feeds over back contacts 120 and 121 of relay 2CTP to relay 2MT so that energy is supplied through transformer 2MDT to relays 2MH and 2IR. Accordingly, relay 2MH picks up while relay 2IR 60 operates to supply impulses of energy to relay 2CTP over the circuit which includes front contact 123 of relay 2MH, front contact 124 of relay 2IR, back contact 126 of relay 3SR, and back contact 127 of relay 3Q.

65 The energy supplied to relay 2CTP causes it to supply energy from battery 2FB to the rails of section 2T and this energy feeds over the back contact of relay 2FCT to relay 2FT and operates it so that energy is supplied through transformer 2FDT to pick up relay 2FH.

In addition, on picking up of relay 2MH energy is supplied over its front contact 128 and back contact 129 of relay 3Q to relay 3LR and 75 its contacts pick up so that its front contact 130

establishes a stick circuit to keep the relay energized as long as relay 3Q is released.

When relay 2SR picked up, its contact 106 transferred control of coding relay 1CTP from relay 1IR to one of the code transmitters. As section 2T is vacant and relay 2FH is picked up, energy of 180 code frequency is supplied to relay 1CTP over the circuit which includes front contact 132 of relay 2FH, front contact 106 of relay 2SR, and back contact 105 of relay 2Q.

In addition, when relay 2SR picked up, its contact 111 connected the primary winding of transformer 1TT across the output terminals of the tuned alternator, while contact 133 of relay 2SR established the circuit to supply energy to the alternator so that energy is supplied from the alternator to the track transformer. As coding relay 1CTP is operated at the 180 code rate, alternating current of 180 code frequency is supplied from track transformer 1TT to the rails of section 1T and operates the locomotive cab signal apparatus to provide its clear indication.

When the train advances into section 2T, the supply of energy over the rails of this section is cut off and relay 2FH releases so that its contact 132 transfers control of relay 1CTP to the code transmitter 180CT, while contact 134 of relay 2FH establishes a circuit including front contact 117 of relay 2SR for supplying energy to this coding device. On release of relay 2FH, its contact 135 interrupts one circuit for supplying energy to code transmitter 180CT, but this device is energized by energy supplied thereto over front contact 115 of relay 2SR. Accordingly, relay 2FCT continues to operate to supply energy from battery 2TB to the rails of section 2T.

When the train enters section 2T, relay 2MH releases and energy is supplied over its back contact 128 and front contact 137 of relay 3LR to relay 3SR so that relay 3SR picks up and its contact 138 establishes a stick circuit to keep the relay energized as long as relay 3LR is picked up.

On picking up of relay 3SR, its contact 140 establishes a circuit for the associated coding device 180CT and it operates to cause relay 3FCT to supply master code to the rails of section 3T and thus determine occupancy of this section. If the section is vacant, the equipment for section 3T will operate as explained in connection with section 2T to cause feed-back energy to be supplied over the section rails with the result that relay 3FH is picked up.

When relay 3SR picked up, its contact 126 transferred control of relay 2CTP from relay 2IR to one of the code transmitters, while when relay 3FH picks up, energy of 180 code frequency is supplied to relay 2CTP over the circuit including front contact 141 of relay 3FH, front contact 126 of relay 3SR, and back contact 127 of relay 3Q. As relay 3SR is picked up, the tuned alternator at this location operates to supply energy to the primary winding of track transformer 2TT, and as relay 2CTP is operated at the 180 code rate, alternating current of 180 code frequency is supplied to the rails of section 2T to cause the cab signal apparatus on the locomotive in that section to provide its clear indication.

When the train advances into section 3T, the equipment for that section operates in the same manner as the equipment for section 2T to cause alternating current of appropriate code frequency to be supplied to the section rails at the exit end thereof. When section 3T is occupied, relay 3FH is released and its contact 141 establishes the

circuit for supplying energy of 75 code frequency to relay 2CTP.

When the train vacates section 1T, the energy of 75 code frequency supplied from battery 1FB to the section rails operates relay 1FT so that relay 1FH picks up and its contact 78 establishes a circuit for coding device 1CT. Accordingly, the device 1CT operates to supply energy from battery 1TB to the section rails, and 10 during released periods of the relay 1CTP, this energy feeds to track relay 1MT and operates it so that relay 1MH picks up. When relay 1MH picks up at a time when relay 2SR is picked up, energy is supplied over front contact 114 of relay 2SR and front contact 142 of relay 1MH to relay 2Q, and its contacts pick up so that its contact 144 establishes a stick circuit including front contact 143 of relay 2SR to maintain the relay 2Q picked up as long as relay 2SR is picked up.

In addition, when relay 2Q picks up, its contact 109 interrupts the circuit of relay 2LR while contact 105 of relay 2Q interrupts the circuit of relay 1CTP so that it ceases to cause energy to be supplied from battery 1FB to the rails of section 1T. Accordingly, relay 1FT remains released and relay 1FH releases and its contact 78 interrupts the circuit of coding device 1CT so that energy is no longer supplied to the section rails at the entrance end of the section and relay 1MT remains released and relay 1MH releases.

On release of relay 1MH, its contact 142 interrupts the pick-up circuit of relay 2Q, but this relay is energized by current supplied over its stick circuit so its contacts remain picked up to interrupt the circuits of relays 2LR and 1CTP.

As stated above, on picking up of relay 1MH when relay 2SR is picked up, energy is supplied to relay 2Q and it picks up to interrupt the circuit of relay 2LR. The relay 2LR is of a type the contacts of which are slow to release so they remain picked up for a short period subsequent to picking up of relay 2Q. On release of relay 45 2LR, its contact 112 interrupts the circuit of relay 2SR and after a time interval the contacts of relay 2SR release so that contact 143 interrupts the stick circuit for relay 2Q and relay 2Q thereupon releases and the equipment at the 50 exit end of section 1T is again in its normally deenergized condition.

On release of relay 2SR, its contacts 115 and 117 interrupt the circuits of code transmitters 180CT and 180CT, while contact 133 interrupts 55 the circuit of the tuned alternator and contact 111 short-circuits the primary winding of the track transformer 1TT. In addition, on release of relay 2SR, its contact 106 transfers control of relay 1CTP from the code transmitters to the 60 impulse relay 1IR, but the circuit of relay 1CTP is not complete until relay 2Q releases.

As pointed out above, relay 2Q picked up when energy supplied over the rails of section 1T operated relay 1MT to pick up relay 1MH, while 65 as soon as relay 2Q picks up its contact 105 interrupts the circuit of relay 1CTP so that energy is no longer supplied to the rails of section 1T and, after a short time, relay 1FH releases to discontinue operation of coding device 1CT and 70 thus cut off supply of energy to the entrance end of section 1T so that relay 1MH releases to cause its contact 103 to interrupt the circuit controlled by impulse relay 1IR for supplying energy to the relay 1CTP.

After relay 2Q picks up to interrupt the cir-

cuit of relay **1CTP**, the circuit of relay **1CTP** is not reestablished until relay **2Q** releases, while relay **2Q** remains picked up until relays **2LR** and **2SR** release. The circuit of relay **2SR** is maintained until relay **2LR** releases, while the circuit of relay **2Q** is maintained until relay **2SR** releases so these relays release successively. The relays **2LR**, **2SR** and **2Q** are of a type the contacts of which are slow in releasing, and the various parts of the system are proportioned so that relay **2Q** does not release to establish the circuits of relays **1CTP** and **2LR** until relay **1MH** releases to interrupt the circuits of these relays. This insures that the equipment for section **1T** will be returned to its normally deenergized condition when the section is vacated.

When the train vacates section **2T**, the equipment for this section operates in the same manner as the equipment for section **1T** so that the track section apparatus is deenergized.

The system shown in Fig. 2 operates so that when a train enters the section in the rear of an occupied section, alternating current of 75 code frequency will be supplied to the section rails to cause the locomotive cab signal apparatus to provide its caution indication.

For purposes of illustration, it will be assumed that a train is in section **2T** and that a second or following train enters section **1T**. As explained above, when the first train vacated section **1T**, the equipment for section **1T** was restored to its normally deenergized condition, while relays **2Q**, **2LR** and **2SR** became released. When it is desired to permit the second train to enter section **1T**, the push button **PB** is depressed to pick up the control relay **CR** so that coding device **1CT** operates to supply energy to the rails of section **1T**. This energy operates relay **1MT** to pick up relay **1MH** and thus pick up relay **2LR**, while after relay **1MH** picks up, relay **1CTP** is operated to supply impulses of feed-back energy to the section rails to operate relay **1FT** and pick up relay **1FH** and thus cause signal **1S** to display a permissive indication.

When the second train enters section **1T**, the relay **1MH** releases and relay **2SR** is picked up so that coding device **180CT** operates to cause relay **2FCT** to supply energy to the rails of section **2T**. However, as section **2T** is assumed to be occupied, the energy supplied at the entrance end of the section does not reach the equipment at the exit end of the section so feed-back energy is not supplied over the section rails. Accordingly, relay **2FH** remains released and its contact **132** connects relay **1CTP** to the contact of code transmitter **75CT** and energy of 75 code frequency is supplied to the rails of section **1T**, and the cab signal apparatus on the locomotive in section **1T** will provide its caution indication.

If the first train should vacate section **2T** while the second train is in section **1T**, energy supplied to the rails of section **2T** as a result of operation of relay **2FCT** feeds to relay **2MT** and operates it to pick up relay **2MH** and establish a circuit for relay **3Q** so that it picks up to prevent operation of relay **2CTP** and to cause release of relays **3LR** and **3SR**.

At this time, code transmitter **180CT** at the entrance end of section **2T** is operated by energy supplied thereto over the circuit controlled by relay **2SR** so that this device continues to operate after relay **2CTP** ceases to operate. Accordingly, relay **2MH** remains picked up after release of relays **3LR**, **3SR** and **3Q** and, as soon as relay **3Q** releases, energy is supplied to relay **75**

2CTP over the circuit controlled by relay **2IR** so that relay **2CTP** operates to supply feed-back energy to the rails of section **2T**. This energy operates relay **2FT** so that relay **2FH** picks up to transfer control of relay **1CTP** from the coder **75CT** to the coder **180CT** with the result that energy of 180 code frequency is supplied to the rails of section **1T** and the indication displayed by the cab signal apparatus on the locomotive in that section is changed from caution to clear.

The system shown in Fig. 2 also operates so that, if a train enters an occupied section, the equipment will function to cause the cab signal apparatus on the locomotive of the second train to provide an appropriate indication.

For purposes of illustration, it will be assumed that a train is in section **2T** and that a second or following train enters the section. The rails of section **2T** are shunted by the first train in the section so the cab signal apparatus on the locomotive of the second train will provide its most restrictive indication when the locomotive enters section **2T**.

As explained above, when the first train entered section **2T**, the relay **3SR** picked up so that relay **2CTP** is operated by energy supplied over a circuit controlled by one of the code transmitters and energy from both the battery **2FB** and the transformer **2TT** is supplied to the rails of section **2T**. As long as section **3T** is vacant, relay **3FH** is picked up so relay **2CTP** is operated at the 180 code rate, but when the first train in section **2T** advances into section **3T**, the relay **3FH** releases and transfers control of relay **2CTP** to code transmitter **75CT** so that energy of 75 code frequency is supplied to the rails of section **2T**. When the first train vacates section **2T**, the energy supplied to the section rails as a result of operation of relay **2CTP** causes the cab signal apparatus on the locomotive of the second train to provide its caution indication.

Because of the presence of the second train in section **2T**, the energy supplied from battery **2FB** to the section rails does not reach relay **2FT** and relay **2FCT** is not operated to supply energy from battery **2TB** over the rails of section **2T** to operate relay **2MT** and pick up relay **2MH**. Relay **2MH** therefore remains released and does not establish the circuit of relay **3Q** and the equipment at the exit end of section **2T** continues to operate to supply to the rails of section **2T** energy of a code frequency determined by traffic in section **3T**. When section **2T** is vacated, the equipment for the section operates in the usual manner to cease operation and assume its normally deenergized condition.

Modification shown in Fig. 3

In Fig. 3, there is shown a modified form of apparatus which I may enjoy. This modification is similar to that shown in Fig. 2 but differs therefrom in the control of the relay **FCT**. Under vacant track conditions, the relay **LR** is released and connects relay **FCT** to a secondary winding of the recoding transformer **FDT**. On approach of a train, the relay **LR** is picked up, as explained in connection with Figs. 1 and 2, and connects relay **FCT** to the circuit controlled by the code transmitter **180CT** so that relay **FCT** operates to supply coded energy to the rails of the associated track section.

On movement of a train through the track stretch, the relay **LR** releases when the section in the rear is vacated, while on release of relay **LR**, control of relay **FCT** is transferred to the

decoding transformer FDT. As long as the section is occupied, relay FT remains released and no energy is supplied from the decoding transformer FDT to relay FCT. When the section with which relay FCT is associated is vacated, energy supplied at the exit end of the section feeds over the section rails and operates relay FT so that an impulse of energy effective to pick up the contacts of relay FCT is supplied to the relay each time the contacts of relay FT release. As a result of operation of relay FCT, energy is supplied from battery TB to the section rails, while, as explained in connection with Fig. 2, this energy causes the equipment at the exit end of the section to operate to discontinue the supply of energy to the section rails at that point so that relay FT ceases to operate and energy is no longer supplied from the transformer FDT to the section rails.

It will be seen that this modification is arranged so that, when a section is vacated, the relay FCT ceases to operate and therefore discontinues the supply of energy to the section rails substantially as soon as the supply of energy to the exit end of the section is cut off. It is unnecessary to wait for release of relay FH before operation of relay FCT to supply energy to the section rails is discontinued. The prompt termination of the supply of energy to the section rails as a result of operation of relay FCT is desirable as it makes deenergization of the apparatus for a track section prompt and positive.

Although I have herein shown and described only two forms of normally deenergized coded signaling system embodying my invention together with a modification thereof which I may employ, it is to be understood that various changes and modifications may be made therein within the scope of the appended claims without departing from the spirit and scope of my invention.

Having thus described my invention, what I claim is:

1. In combination, a stretch of railway track through which traffic normally moves in a given direction, the rails of said track stretch being divided by insulated joints into a plurality of successive track sections each of which is provided with normally inactive coded track circuit apparatus, means for each section operative on approach of a train to cause coded energy to be supplied to the section rails at the entrance end of the section, the track circuit apparatus for each section being arranged so that on supply of energy to the section rails at the entrance end of the section the equipment at the exit end of the section causes coded energy to be supplied to the section rails at the exit end of the section, traffic governing means for each section responsive to the supply of energy over the rails of the adjacent section in advance from the exit to the entrance end thereof, and means for each section effective on occupancy of the section to supply coded energy to the section rails at the exit end of the section, the track circuit apparatus for each section being arranged so that such supply of coded energy to the section rails at the exit end thereof causes coded energy to be supplied to the section rails at the entrance end of the section when the section is vacated and so that such energy causes the equipment at the exit end of the section to operate to discontinue supply of energy to the section rails at the exit end of the section.

2. In combination, a stretch of railway track divided into a forward and a rearward section each of which is provided with normally inactive

coded track circuit apparatus, means governed by occupancy of the rearward track section for supplying coded energy to the rails of the forward section at the entrance end thereof, means at the exit end of the forward section responsive to supply of coded energy over the section rails to supply coded energy to the section rails at the exit end thereof, traffic governing means for said rearward section responsive to supply of energy over the rails of the forward section from the exit to the entrance end of said forward section, means effective on occupancy of the forward section to supply coded energy to the section rails at the exit end of the section, means at the entrance end of the forward section responsive to supply of energy over the section rails from the exit end thereof to supply coded energy to the section rails at the entrance end thereof, and means at the exit end of the section responsive to the supply of energy over the section rails subsequent to occupancy of the section for cutting off the supply of energy to the section rails at the exit end of the section.

3. In combination, a stretch of railway track divided into a forward and a rearward track section each of which is provided with normally inactive coded track circuit apparatus, a control relay at the exit end of said rearward section which becomes picked up on the supply of coded energy over the rails of said rearward section from the entrance to the exit end thereof, a first and a second normally released auxiliary relay associated with said control relay, means governed by traffic in the track stretch for supplying coded energy to the rails of said rearward section at the entrance end of the section to pick up said control relay and establish a pick-up circuit for said first auxiliary relay, a stick circuit for said first auxiliary relay including its own front contact, means effective when said first auxiliary relay is picked up to supply coded energy to the rails of said forward section at the entrance end thereof, means responsive to supply of coded energy over the rails of the forward section from the entrance to the exit end thereof for supplying coded energy to the rails of the forward section at the exit end thereof, traffic governing means controlled by energy supplied over the rails of said forward section from the exit to the entrance end thereof, a circuit for said second auxiliary relay governed by a back contact of said control relay and a front contact of said first auxiliary relay, means effective when said second auxiliary relay is picked up to supply coded energy to the rails of said rearward section at the exit end thereof, means at the entrance end of said rearward section effective during supply of coded energy over the section rails to supply coded energy to the rails of said rearward section at the entrance end thereof, and means at the exit end of the rearward section operated by energy supplied over the section rails from the entrance to the exit end thereof as a result of supply of energy over the section rails from the exit to the entrance end thereof for interrupting the stick circuit for said first auxiliary relay.

4. In combination, a stretch of railway track divided into a forward, an intermediate and a rearward track section, control means at the exit end of the intermediate section selectively responsive to coded energy of a first or a second type supplied over the section rails from the entrance to the exit end thereof, means responsive to traffic conditions in said rearward section for at times supplying coded energy of said first type

and at other times supplying coded energy of said second type to the rails of said intermediate section at the entrance end thereof, a first and a second normally released auxiliary relay associated with said control means, a pick-up circuit for said first auxiliary relay established only on response of said control means to coded energy of said first type, said first auxiliary relay when picked up establishing for itself a stick circuit which is interrupted on response of said control means to coded energy of said second type, means effective when said first auxiliary relay is picked up to supply to the rails of the forward section at the entrance end thereof coded energy of said first or said second type according as said second auxiliary relay is picked up or released, means responsive to supply of coded energy over the rails of the intermediate section while the second auxiliary relay is released to supply coded energy to the rails of the intermediate section at the exit end thereof, traffic governing means responsive to supply of coded energy over the rails of said intermediate section from the exit to the entrance end thereof, means effective on deenergization of said control means when the first auxiliary relay is picked up to establish a circuit for said second auxiliary relay, means for supplying coded energy to the rails of said intermediate section at the exit end thereof when said second auxiliary relay is picked up provided the first auxiliary relay is also picked up, and means at the entrance end of said intermediate section responsive to supply of coded energy over the section rails to supply coded energy of said second type to the section rails.

5. In a normally deenergized coded railway signaling system, in combination, a stretch of railway track divided into a plurality of track sections through which traffic normally moves in a given direction, means for projecting coded detector energy over the rails of the track stretch away from the entrance end of the stretch for a selected number of track sections, means for each section responsive to the supply of coded detector energy over the section rails for supplying coded control energy over the section rails towards the entrance end of the stretch, traffic governing means responsive to supply of coded control energy over the rails of said track sections, means operative on entrance of a train into each section to cause the supply of coded detector energy to be projected into another track section, and means for each section for detecting when the section has been vacated and for thereupon discontinuing operation of the track circuit apparatus for the said section.

6. In a normally deenergized coded railway signaling system, in combination, a stretch of railway track divided into a plurality of track sections through which traffic normally moves in a given direction, means for projecting coded detector energy away from the entrance end of the stretch over the rails of the two track sections nearest the entrance end of the stretch, means for each section responsive to the supply of coded detector energy over the section rails for supplying over the section rails towards the entrance end of the stretch coded control energy, the supply of coded control energy to the rails of each of said track sections being governed by means responsive to the supply of coded control energy over the rails of the adjacent track section in advance thereof, traffic governing means for each section responsive to the supply of coded control energy over the rails of said section, means oper-

ative on entrance of a train into each track section to cause coded detector energy to be supplied to the second track section in advance thereof, and means for each track section for detecting when the section has been vacated and for thereupon discontinuing operation of the track circuit apparatus for the said section.

7. In a normally deenergized coded railway signaling system, in combination, a stretch of railway track divided into a plurality of track sections through which traffic normally moves in a given direction, means for projecting coded detector energy away from the entrance end of the stretch over the rails of the two track sections nearest the entrance end of the stretch, means for each section responsive to the supply of coded detector energy over the section rails for supplying over the section rails towards the entrance end of the stretch coded control energy of a first or a second type according as coded control energy is or is not being transmitted over the rails of the adjacent track section in advance, traffic governing means for each section governed by the supply of coded control energy over the rails of the said section and selectively responsive to the type of such energy, means operative on entrance of a train into each track section to cause coded detector energy to be supplied to the second track section in advance, and means for each track section for detecting when the section has been vacated and for thereupon discontinuing operation of the track circuit apparatus for the said section.

8. In a normally deenergized coded railway signaling system, in combination, a stretch of railway track divided into a plurality of track sections through which traffic normally moves in a given direction, means for projecting coded detector energy of normal polarity away from the entrance end of the track stretch over the rails of the track section nearest the entrance end of the stretch, means for each section operative on the supply of coded detector energy of normal polarity over the section rails to cause coded detector energy of reverse polarity to be projected away from the entrance end of the track stretch over the rails of the adjacent section in advance, means for each section responsive to the supply of coded detector energy of either polarity over the section rails for supplying over the section rails towards the entrance end of the stretch coded control energy, means for each section responsive to the supply of coded control energy over the rails of the said section and controlling the polarity of the coded control energy supplied to the rails of the adjacent track section in the rear, traffic governing means for each section governed by the supply of coded control energy over the rails of the said section and selectively responsive to the polarity of such energy, means for each section operative on entrance of a train into the said section to cause the coded detector energy supplied to the adjacent section in advance to be changed from reverse to normal polarity, and means for each track section for detecting when the section has been vacated and for thereupon discontinuing operation of the track circuit apparatus for the said section.

9. In a normally deenergized coded railway signaling system, in combination, a stretch of railway track divided into a plurality of track sections through which traffic normally moves in a given direction, means for projecting coded detector energy of normal polarity away from

the entrance end of the track stretch over the rails of the track section nearest the entrance end of the stretch, each section having at the exit end thereof a first auxiliary relay having a pick-up circuit which is established when and only when coded detector energy of normal polarity is supplied over the rails of the said section, each first auxiliary relay when picked up establishing for itself a stick circuit which is interrupted on supply of coded energy of reverse polarity over the rails of the associated track section, each track section having at the exit end thereof a second auxiliary relay which is energized when the supply of coded detector energy over the rails of said section is cut off provided the associated first auxiliary relay is picked up, each first auxiliary relay when energized causing to be supplied to the rails of the adjacent track section in advance coded detector energy of normal or reverse polarity according as the associated second auxiliary relay is picked up or released, means for each section responsive to the supply of coded detector energy of either polarity over the section rails and to the supply of coded control energy over the rails of the adjacent section in advance for supplying coded control energy over the rails of the associated section towards the entrance end thereof, means responsive to coded control energy supplied over the rails of said track sections for governing traffic in said track stretch, and means for each track section for detecting when the section has been vacated and for thereupon discontinuing operation of the track circuit apparatus for the said section.

10. In a normally deenergized coded railway signaling system, in combination, a stretch of railway track divided into a plurality of track sections through which traffic normally moves in a given direction, means for projecting coded detector energy of normal polarity away from the entrance end of the track stretch over the rails of the track section nearest the entrance end of the stretch, each section having at the exit end thereof a first auxiliary relay having a pick-up circuit which is established when and only when coded detector energy of normal polarity is supplied over the rails of the said section, each first auxiliary relay when picked up establishing for itself a stick circuit which is interrupted on supply of coded energy of reverse polarity over the rails of the associated track section, each track section having at the exit end thereof a second auxiliary relay which is energized when the supply of coded detector energy over the rails of said section is cut off provided the associated first auxiliary relay is picked up, each first auxiliary relay when energized causing to be supplied to the rails of the adjacent track section in advance coded detector energy of normal or reverse polarity according as the associated second auxiliary relay is picked up or released, means for each section responsive to the supply of coded detector energy of either polarity over the section rails for supplying over the section rails towards the entrance end thereof coded control energy of normal or reverse polarity according as coded control energy is or is not being supplied over the rails of the adjacent track section in advance, means responsive to coded control energy supplied over the rails of said track sections and selectively responsive to the polarity of such energy for governing traffic in said track stretch, and means for each track section for detecting when the section has been vacated and for thereupon

discontinuing operation of the track circuit apparatus for the said section.

11. In a normally deenergized coded railway signaling system, in combination, a stretch of railway track divided into a plurality of track sections through which traffic normally moves in a given direction, means for projecting coded detector energy of normal polarity away from the entrance end of the track stretch over the rails of the track section nearest the entrance end of the stretch, each section having at the exit end thereof a first auxiliary relay having a pick-up circuit which is established when and only when coded detector energy of normal polarity is supplied over the rails of the said section, each first auxiliary relay when picked up establishing for itself a stick circuit which is interrupted on supply of coded energy of reverse polarity over the rails of the associated track section, each track section having at the exit end thereof a second auxiliary relay which is energized when the supply of coded detector energy over the rails of said section is cut off provided the associated first auxiliary relay is picked up, each first auxiliary relay when energized causing to be supplied to the rails of the adjacent track section in advance coded detector energy of normal or reverse polarity according as the associated second auxiliary relay is picked up or released, means for each section responsive to the supply of coded detector energy of either polarity over the section rails and to the supply of coded control energy over the rails of the adjacent section in advance for supplying coded control energy over the rails of the associated section towards the entrance end thereof, means responsive to coded control energy supplied over the rails of said track sections for governing traffic in said track stretch, means for each section operative when the first and second auxiliary relays for such section are picked up to supply coded resetting energy to the section rails at the exit end thereof, and means for each section responsive to the supply of coded resetting energy over the section rails for supplying to the section rails at the entrance end thereof coded energy the polarity of which is governed by the second auxiliary relay for the adjacent track section in the rear.

12. In a normally deenergized coded railway signaling system, in combination, a stretch of railway track divided into a plurality of track sections through which traffic normally moves in a given direction, means for projecting coded detector energy of normal polarity away from the entrance end of the track stretch over the rails of the track section nearest the entrance end of the stretch, each section having at the exit end thereof a first auxiliary relay having a pick-up circuit which is established when and only when coded detector energy of normal polarity is supplied over the rails of the said section, each first auxiliary relay when picked up establishing for itself a stick circuit which is interrupted on supply of coded energy of reverse polarity over the rails of the associated track section, each track section having at the exit end thereof a second auxiliary relay which is energized when the supply of coded detector energy over the rails of said section is cut off provided the associated first auxiliary relay is picked up, each first auxiliary relay when energized causing to be supplied to the rails of the adjacent track section in advance coded detector energy of normal or reverse polarity according as the associated second auxiliary relay is picked up or released, means for

each section responsive to the supply of coded detector energy of either polarity over the section rails for supplying over the section rails towards the entrance end thereof coded control energy of normal or reverse polarity according as coded control energy is or is not being supplied over the rails of the adjacent track section in advance, means responsive to coded control energy supplied over the rails of said track sections and selectively responsive to the polarity of such energy for governing traffic in said track stretch, means for each section operative when the first and second auxiliary relays for such section are picked up to supply coded resetting energy to the section rails at the exit end thereof, and means for each section responsive to the supply of coded resetting energy over the section rails for supplying to the section rails at the entrance end thereof coded energy the polarity of which is governed by the second auxiliary relay for the adjacent track section in the rear.

13. In a normally deenergized coded railway signaling system, in combination, a stretch of railway track through which traffic normally moves in a selected direction, the rails of said track stretch being divided by insulated joints into a plurality of successive track sections, means for each section governed by the supply of coded energy over the rails of the adjacent track section in the rear from the entrance to the exit end thereof for supplying coded energy to the section rails at the entrance end of the section, means for each section responsive to supply of coded energy over the section rails from the exit end of the section for also supplying coded energy to the section rails at the entrance end thereof, means for each section responsive to the supply of coded energy over the section rails from the entrance end thereof for supplying coded energy to the section rails at the exit end thereof, means for each section effective during occupancy thereof for also supplying coded energy to the section rails at the exit end of the section, and means governed by coded energy supplied over the rails of said sections from the exit to the entrance end thereof for controlling traffic in said stretch.

14. In a normally deenergized coded railway signaling system, in combination, a stretch of railway track through which traffic normally moves in a selected direction, the rails of said track stretch being divided by insulated joints into a plurality of successive track sections, means for each section governed by the supply of coded energy over the rails of the adjacent track section in the rear from the entrance to the exit end thereof for supplying coded energy to the section rails at the entrance end of the section, means for each section responsive to supply of coded energy over the section rails from the exit end of the section for also supplying coded energy to the section rails at the entrance end thereof, means for each section responsive to the supply of coded energy over the section rails from the entrance end thereof for supplying coded energy to the section rails at the exit end thereof, means for each section effective during occupancy thereof for also supplying coded energy to the section rails at the exit end of the section, and traffic governing means for each section controlled by coded energy supplied over the rails of the adjacent section in advance from the exit to the entrance end thereof.

15. In a normally deenergized coded railway signaling system, in combination, a stretch of

railway track through which traffic normally moves in a given direction, the rails of said track stretch being divided by insulated joints into a plurality of successive track sections, each section having at the entrance end thereof a normally released auxiliary relay which becomes picked up when and only when coded energy of a first type is supplied over the rails of the adjacent section in the rear from the entrance to the exit end thereof and which when picked up remains picked up until coded energy of a second type is supplied over the rails of the adjacent section in the rear from the entrance to the exit end thereof, each auxiliary relay when picked up causing coded energy to be supplied to the rails of the associated section at the entrance end thereof, means for each section responsive to the supply of coded energy over the section rails from the exit end thereof for also supplying coded energy to the section rails at the entrance end thereof, means for each section for causing the coded energy supplied to the section rails at the entrance end thereof to be of said first or said second type according as the adjacent section in the rear is occupied or is unoccupied, means for each section responsive to the supply of coded energy over the section rails from the entrance end thereof to supply coded energy to the section rails at the exit end of the section, means for each section controlled by the auxiliary relay of the adjacent section in advance for also supplying coded energy to the section rails at the exit end thereof, each section having a wayside signal at the entrance end thereof, and means for each section responsive to the supply of coded energy over the section rails from the exit end thereof for controlling the signal for the section.

16. In a normally deenergized coded railway signaling system, in combination, a stretch of railway track through which traffic normally moves in a given direction, the rails of said track stretch being divided by insulated joints into a plurality of successive track sections, each section having at the entrance end thereof a normally released auxiliary relay which becomes picked up when and only when coded energy of a first type is supplied over the rails of the adjacent section in the rear from the entrance to the exit end thereof and which when picked up remains picked up until coded energy of a second type is supplied over the rails of the adjacent section in the rear from the entrance to the exit end thereof, each auxiliary relay when picked up causing coded energy to be supplied to the rails of the associated section at the entrance end thereof, means for each section responsive to the supply of coded energy over the section rails from the exit end thereof for also supplying coded energy to the section rails at the entrance end thereof, means for each section for causing the coded energy supplied to the section rails at the entrance end thereof to be of said first or said second type according as the adjacent section in the rear is occupied or is unoccupied, means for each section responsive to the supply of coded energy over the section rails from the entrance end thereof to supply coded energy to the section rails at the exit end of the section, means for each section controlled by the auxiliary relay of the adjacent section in advance for also supplying coded energy to the section rails at the exit end thereof, each section having at the entrance end thereof a wayside signal including a lamp, means for light-

ing the lamp of each signal only when the auxiliary relay of the section with which the signal is associated is picked up, and means for each section responsive to the supply of coded energy over the section rails from the exit end thereof for controlling the signal for the section.

17. In a normally deenergized coded railway signaling system, in combination, a stretch of railway track through which traffic normally moves in a given direction, the rail of said track stretch being divided by insulated joints into a plurality of successive track sections, each section having at the entrance end thereof a normally released auxiliary relay which becomes picked up when and only when coded energy of a first type is supplied over the rails of the adjacent section in the rear from the entrance to the exit end thereof and which when picked up remains picked up until coded energy of a second type is supplied over the rails of the adjacent section in the rear from the entrance to the exit end thereof, each auxiliary relay when picked up causing coded energy to be supplied to the rails of the associated section at the entrance end thereof, means for each section responsive to the supply of coded energy over the section rails from the exit end thereof for also supplying coded energy to the section rails at the entrance end thereof, means for each section for causing the coded energy supplied to the section rails at the entrance end thereof to be of said first or said second type according as the adjacent section in the rear is occupied or is unoccupied, means for each section responsive to the supply of coded energy over the section rails from the entrance end thereof for supplying to the section rails at the exit end thereof coded energy which is of a first or a second type according as coded energy is or is not being supplied over the rails of the adjacent section in advance, means for each section controlled by the auxiliary relay of the adjacent section in advance for also supplying coded energy to the section rails at the exit end thereof, each section having a wayside signal at the entrance end thereof, and means for each section controlled by coded energy supplied over the section rails from the exit end thereof and selectively responsive to the type of such energy for controlling the signal for the section.

18. In a normally deenergized coded railway signaling system, in combination, a stretch of railway track through which traffic normally moves in a given direction, the rails of said track stretch being divided by insulated joints into a plurality of successive track sections, each section having at the entrance end thereof a first, a second and a third normally released auxiliary relay, each first auxiliary relay being picked up on the supply of coded energy over the rails of the adjacent section in the rear from the entrance end thereof provided the associated third auxiliary relay is released, each second auxiliary relay being picked up when the supply of coded energy over the rails of the adjacent section in the rear is cut off and the associated first auxiliary relay is picked up, each second auxiliary relay when picked up remaining picked up as long as the associated third auxiliary relay remains released, each third auxiliary relay being picked up on the supply of coded energy over the rails of the adjacent section in the rear from the entrance end thereof provided the associated second auxiliary relay is picked up, each second auxiliary relay when picked up causing coded direct current energy to be supplied to the rails of the associated section at the entrance end thereof and also causing to be supplied to the rails of the adjacent section in the rear at the exit end thereof coded alternating and direct current which is of a first or a second code frequency according as coded energy is or is not being supplied over the rails of the associated section from the exit end thereof, means for each section responsive to the supply of coded direct current over the section rails from the exit end thereof for also causing coded energy to be supplied to the section rails at the entrance end thereof, and means for each section responsive to the supply of coded energy over the section rails from the entrance end thereof for also causing coded direct current to be supplied to the section rails at the exit end thereof.

5 picked up on the supply of coded energy over the rails of the adjacent section in the rear provided the associated second auxiliary relay is picked up, each second auxiliary relay when picked up causing coded energy to be supplied to the rails of the associated section at the entrance end thereof and also causing to be supplied to the rails of the adjacent section in the rear at the exit end thereof coded energy which is of a first or a second type according as coded energy is or is not being supplied over the rails of the associated section from the exit end thereof, means for each section responsive to the supply of coded energy over the section rails from the exit end thereof for also causing coded energy to be supplied to the section rails at the entrance end thereof, means for each section responsive to the supply of coded energy over the section rails from the entrance end thereof for also causing coded energy to be supplied to the section rails at the exit end thereof, and traffic governing means for each section responsive to the type of coded energy supplied to the section rails at the exit end of the section.

25 19. In a normally deenergized coded railway signaling system, in combination, a stretch of railway track through which are operated in a given direction locomotives equipped with cab signal apparatus responsive to the flow of coded 30 alternating current in the track rails, the rails of said track stretch being divided by insulated joints into a plurality of successive track sections, each section having at the entrance end thereof a first, a second and a third normally 35 released auxiliary relay, each first auxiliary relay being picked up on the supply of coded energy over the rails of the adjacent section in the rear from the entrance end thereof provided the associated third auxiliary relay is released, each second auxiliary relay being picked up when the supply of coded energy over the rails of the adjacent section in the rear is cut off and the associated first auxiliary relay is 40 picked up, each second auxiliary relay when picked up remaining picked up as long as the associated third auxiliary relay remains released, each third auxiliary relay being picked up on the supply of coded energy over the rails of the adjacent section in the rear provided the associated second auxiliary relay is picked up, each second auxiliary relay when picked up causing coded direct current energy to be supplied to the rails of the associated section at the entrance end thereof and also causing to be supplied to the rails of the adjacent section in the rear at the exit end thereof coded alternating and direct current which is of a first or a second code frequency according as coded energy is or is not being supplied over the rails of the associated section from the exit end thereof, means for each section responsive to the supply of coded direct current over the section rails from the exit end thereof for also causing coded energy to be supplied to the section rails at the entrance end thereof, and means for each section responsive to the supply of coded energy over the section rails from the entrance end thereof for also causing coded direct current to be supplied to the section rails at the exit end thereof.

55 70 ARTHUR L. JEROME.
